UNITED STATES PATENT OFFICE

100,838

DESIGN FOR A COMBINED GAUGE AND ILLUMINATION HOUSING

Harry S. Baker, Arlington, and Joseph W. Motherwell, Melrose, Mass., assignors to The Ashton Valve Company, Cambridge, Mass., a corporation of Massachusetts

Application May 8, 1936, Serial No. 62,554

Term of patent 14 years

To all whom it may concern:

Be it known that we, Harry S. Baker, a British subject and resident of Arlington, in the county of Middlesex and Commonwealth of Massachusetts, and Joseph W. Motherwell, a citizen of the United States and resident of Melrose, in the county of Middlesex and Commonwealth of Massachusetts, have invented a new, original, and ornamental Design for a Combined Gauge and Illumination Housing, of which the following is a specification, reference being had to the accompanying drawing, forming part thereof.

Figure 1 is a front elevation of a combined gauge and illumination housing showing our new design; and

Figure 2 is a side elevation thereof.

We claim:

The ornamental design for a combined gauge and illumination housing, as shown.

HARRY S. BAKER.
JOSEPH W. MOTHERWELL.
